UNITED STATES PATENT OFFICE

JOHN WARREN VEDDER, OF WORCESTER, MASSACHUSETTS, ASSIGNOR TO RICE, BARTON & FALES, INCORPORATED, OF WORCESTER, MASSACHUSETTS, A CORPORATION OF MASSACHUSETTS

PAPER DRIER

Application filed July 25, 1928. Serial No. 295,226.

This invention relates to a drier for the wet newly formed web as it comes from the web end of the paper making machine.

The principal objects of the invention are 5 to provide a relative location for the steam cylinders or drums over which the web passes, so as to economize in the horizontal space required for the drier; to provide a construction in which the soft paper web can be held 10 against the steam drums by a felt arrangement, which will serve as a means of passing the paper web around the steam drums as well as holding the paper web tightly against the surface of the same, thus increasing the drying 15 capacity of the steam drums; and to provide a means for additionally drying this felt so that it will be in a highly dried condition when it comes into contact with the paper web when it reaches the first drying drum.

20 As is well known to those skilled in the art of paper making, it frequently occurs that the paper web breaks and winds itself around the steam drums in several layers, and that with the conventional horizontal drier construction 25 it is a difficult matter to remove this paper due to interference of framework, gears, etc. With the arrangement of the framework and gearing provided in this arrangement it will clearly be understood that the 30 removal of these layers of paper is facilitated as the same may be speared at the open space on the steam drums between the paper rolls.

With the conventional horizontal drier construction, the driving side of the machine 35 presents a wall of drier drums spur gears, making it impossible to gain access to spear the paper from the driving side of the machine, whereas with this construction the 40 gears being small in diameter and entirely covered by guards the machine will be as accessible from the driving side as it is from the tending side. It will also be possible with this construction to gain access to the 45 main drum bearings and felt and paper roll bearings for purposes of inspection and oiling, the gearing presenting no obstacle as to accessibility.

Other objects and advantages of the invention will appear hereinafter.

50 Reference is to be had to the accompany-

ing drawing which is a side elevation, partly diagrammatic, of a drier constructed in accordance with this invention.

The drying is done by a number of series 55 of steam drying drums 10, each series arranged vertically. The journals of these drums are supported in bearings on the sides of the drier, not shown. Each drum is provided with a gear 11 on one end and between each two of these gears is a transmitting or 60 driving gear 12, which transmit power from the driving shaft throughout the vertical series. The gears 11 and 12 are shown as of the same size or substantially so, and covered by guards 9. One of the gears 12 of 65 each vertical series is on a power shaft and drives that series of drums.

It will be observed that these drying drums are located directly one over the other with a space between them in each series. The 70 web of paper 13 comes into the machine at the left, as shown in the figure, passes over the first drum and then over guide rolls 14, two of which are shown, to the second drum and so on from the bottom to the top of that series. 75

At the top the web passes over a series of 80 paper carrying rolls to the top drum 10 of the next series, and then it passes down through the series in the same manner as described above.

It will be noticed that it does not pass to 85 the bottom drying drum 10^a. On the contrary, it passes over a carrying roll 16 to the next to the bottom drum 10 of the next series, then upwardly through that series over another set of carrying rolls 15 and down the next series of drums and carrying rolls 14 to the bottom where it passes out of the driers over a carrying roll 17, thoroughly dried. 90 As many of these series of drums can be used as may be desired in view of the condition and character of the paper being made.

In this machine it is desired to employ an 95 endless felt blanket 20 to hold the paper on the drums and keep it in position thereon and in close contact therewith. Although this felt is endless it may be considered as entering at the same point as the web 13 and passing over the bottom drum 10 outside this web. It then passes to a felt carrying roll 21 which 100

is located in the triangle formed by the web passing over the two carrying rolls 14 and the two drums from and to which the web passes.

This enables the felt to be wound around the second drum 10 on the outside of the paper web and so on to the top of the first series of drums, and then it passes upwardly from this drum over rolls 22, which may be arranged, if desired, to guide it automatically and then down on the outside of the web on the top drum of the next series and then passes around carrying rolls 21 in the same manner as above described, down to and over the next to the bottom drum 10. Then it is passed over a roll 23 and up around the next series of drums as in the case of the paper.

From the bottom drum of the last series it passes over a series of carrying rolls 24. I have shown three of these rolls which can be arranged to automatically stretch, guide and tension the felt which, of course, has received a good deal of moisture from the paper in its travel over the drums. It then passes over a hand-adjusting carrying roll 25 and around the two drums 10^a which are steam heated like the drums 10 and driven in the same way. It is by these drums that the felt is dried out so as to be ready to pass back over similar carrying rolls 25 and 24 to the first drum 10.

In this way the horizontal space is economized over that type of driers in which the web passes around a series of drying drums located in horizontal alignment. In fact, with the design shown, the same amount of drying is secured in a little more than a quarter of the space usually occupied. The drying of the felt 20 is arranged so that without any reversal or complicated mechanism it always comes on the outside of the paper web on each drum. It is automatically adjusted by the rolls 24 and re-dried every time it comes around, by the drums 10^a.

The arrangement of gearing provides for the driving of the drums in each series always in the same direction and uniformly, and the open spaces in the triangles in the web of paper provide for the escape of the moisture at the side so that most of it will not escape at the ends of the drums, and thus concentrate the moisture of the escaping air at the ends. The driving of the drums by the series of small gears leaves more space so that the paper can be speared from the driving side.

This constitutes an efficient means and space saving device for the drying of a paper web continuously.

Although I have illustrated and described only a single form of the invention, I am aware of the fact that modifications can be made therein by any person skilled in the art without departing from the scope of the invention as expressed in the claims.

Therefore, I do not wish to be limited in this respect, but what I do claim is:—

1. In a paper web drier, the combination with a plurality of vertical series of drying drums and means for driving them, of guides located adjacent to the drums for receiving a drying blanket from each drum and delivering it to the next drum, and means for drying the said blanket between the time it leaves the last drum of the drier and the time it is directed to the surface of the first one. 70

2. In a drier for a paper web, the combination with a plurality of series of horizontal drums arranged in vertical alignment for receiving the continuous web of paper and passing it through the series, a heated drum of one of the intermediate series at the bottom being arranged to receive a blanket and dry it, and means for guiding the blanket to the surface of one of the paper web drying drums and thereon through the series back to the blanket drying drum. 80

3. In a drier for a paper web, the combination of a plurality of series of heated drums for receiving the continuous web of paper and passing it through the series, a heated drum of one of the intermediate series being arranged to receive a blanket and dry it, and means for guiding the blanket away from the paper to the surface of one of the paper web drying drums and therefrom through the series back to the blanket drying drum. 90

4. In a paper web drier, the combination of a plurality of series of drying drums, and means for driving all the drums of each series from a single shaft, with means for guiding the paper web around all but one of the drums of each pair of series of drums, and means for guiding a drying blanket around the same drums and then back over the other drum of each series for drying out the blanket and finally back to the first drum of the series. 100

5. In a drier for a paper machine, the combination with a series of heated drying drums arranged in a vertical row, a gear on each drum, an intermediate gear between each two drum gears meshing with both, all of said gears being substantially the same size and of less diameter than the drums, whereby it is possible to spear the paper on the drums from the driving side of the drier and guards over the gears. 110

In testimony whereof I have hereunto affixed my signature. 115
